PRINTER'S GAUGE

Carl J. Winkvist, Mattapan, Mass.

Application February 25, 1949, Serial No. 78,427

2 Claims. (Cl. 101—415)

1

This invention relates to printer's gages of the type used in connection with platen printing presses for positioning correctly the individual sheets as they are fed to the platen to receive the imprint.

In the operation of a printing press of this type it is common practice to employ a so-called "tympan sheet" which is secured to the platen and to which said gages or sheet-positioning members are clamped.

If the material being printed is in the form of cards or heavy material like cardboard, it sometimes happens that the repeated feeding movement of such cards or cardboard into printing position against the gages clamped to the tympan sheet will cause a slight shifting in position of one or more of the gages, and if this occurs, the improperly placed gages will fail to hold the card or sheet in proper position for printing and an imperfect print will result.

This is especially noticeable in color printing which involves making on each sheet two or more imprints of different colors, because if the successive imprints on any sheet do not match exactly, the final imprint will be defective.

It is therefore important that the printing gage should be of such a character that when it is clamped to the tympan sheet in proper position it will maintain such position during any run of the press even though the material which is being printed is heavy material such as cardboard.

One of the objects of the invention is to provide a printer's gage which has this characteristic.

Another object is to provide a printer's gage which can be easily set in the proper position on a tympan sheet and then clamped thereto with one hand only.

Another object is to provide a printer's gage which can be firmly clamped to a tympan sheet with the sheet-positioning head of the gage within a very short distance, on the order of $\frac{1}{8}$ ", from the edge of the tympan sheet thereby increasing the range of work that can be done on any given press.

A further object of the invention is to provide a printer's gage which will be clamped with equal firmness on a tympan sheet whether the latter is a relatively thin sheet or a relatively thick sheet.

Other features of the invention are to improve printer's gages in the various particulars herein-after set forth.

Referring now to the drawings, wherein I have shown a selected embodiment of my invention,

Fig. 1 is a top plan view of a gage embodying the invention.

2

Fig. 2 is a side view thereof showing the clamping member closed.

Fig. 3 is a side view showing the clamping member open.

5 Fig. 4 is an enlarged sectional view on the line 4—4, Fig. 1 showing the gage clamped to a tympan sheet.

Fig. 5 is a section on the line 5—5, Fig. 1 showing the gage clamped to a tympan sheet.

10 Fig. 6 illustrates the platen of a printing press having gages clamped to the tympan sheet thereof for properly positioning a sheet to be printed.

Fig. 7 is a perspective view of the gage.

Fig. 8 is an enlarged sectional view on the line 8—8, Fig. 5.

15 Fig. 9 is a fragmentary sectional view on an enlarged scale illustrating the manner in which the gage head is clamped to the tympan sheet.

Referring first to Fig. 6, 1 indicates the platen

20 of a printing press to which is secured the usual tympan sheet 2, 3 indicates a card or sheet on which the imprint is to be made, and 4 indicates gages embodying my invention by which the sheet 3 is properly positioned.

25 My improved gage includes in its construction a base plate member 5 and a clamping member 6, the two members preferably being made from a single piece of sheet metal which is bent into substantially U formation as shown, thereby to provide a space 7 between them to receive one edge of the tympan sheet 2.

30 The device also includes a clamp-actuating member 8 by which clamping pressure can be applied to the clamping member 6. The clamp-actuating member 8 is preferably made from sheet material and one end 9 thereof is bent at an angle to provide a presser foot. The clamp-actuating member is mounted for turning movement in two ears 10 that extend upwardly from the opposite sides of the base element, said clamp-actuating member being provided with trunnions 11 which operate in openings 12 formed in said ears.

35 The clamp-actuating member is so constructed that when it is swung into its open position shown in Figs. 3 and 7, the clamping member 6 is relieved from pressure, but when the clamp-actuating member is thrown into its operative clamping position shown in Figs. 2 and 3, the presser foot portion 9 thereof presses downwardly on the clamping member 6.

40 The gage is so made that the resiliency of the material at the bight portion 13 will raise the clamping member from the base member when the clamp-actuating member is swung into its operative position as shown in Figs. 3 and 7.

45 50 55

The clamping member 6 is bent upwardly at its outer or free end as shown at 14 and then is bent downwardly as indicated at 15, said downwardly bent portion 15 constituting a gage head or work-positioning portion. The portions 14 and 15 of the clamping member thereby have an inverted U-shaped form.

The free end 16 of the base element is provided with a biting edge 17 and the lower edge face of the gage head 15 also presents a companion biting edge 18, said biting edges being parallel to each other and situated substantially in the same vertical plane. The biting edge 18 on the gage head is constituted by the corner where the bottom edge face 19 of the gage head meets the inner vertical face 20 thereof and the gage head is so formed that this edge face 19 of the gage head is situated slightly below the under face 21 of the body of the clamping member.

Moreover the edge face 19 of the gage head 15 overhangs the end face 16 of the base member as clearly seen in Fig. 4, so that when the tympan sheet 2 is placed between the base plate and the clamping member, said edge face is directly over the portion 22 of the tympan sheet that is located immediately beyond the end of the base plate and which is therefore unsupported.

When the tympan sheet has thus been placed between the clamping member and the base element and the clamp-actuator 8 is operated to apply a clamping pressure to the clamping member, the end face 19 of the gage head, which may be referred to as a tympan sheet engaging face, will be pressed against the upper face of the unsupported portion 22 of the tympan sheet and said portion will be displaced downwardly just beyond the end face 16 of the base element 5. During this operation the biting edge 18 of the clamping member and the biting edge 17 of the base plate are pressed into the top and bottom faces of the tympan sheet and a forwardly facing shoulder 23 is formed on the top face of the tympan sheet immediately in the rear of the gage head 15, and a rearwardly facing shoulder 24 is formed in the bottom face of the tympan sheet immediately in front of the end edge 16 of the base element as shown in Figs. 4 and 9. Such downward displacement of the portion 22 of the tympan sheet is a bodily downward movement in a horizontal plane (see Fig. 9) as distinguished from a bending of the tympan sheet around the edge of the base plate. Moreover, the sinking of the biting edge 18 into the top face of the tympan sheet, as well as the sinking of the biting edge 17 of the base plate into the bottom face of the tympan sheet, is in the nature of a shearing action and does not involve bending the tympan sheet around the under edge of the base.

The gage is so constructed that when clamping pressure is applied to the clamping member as shown in Fig. 4, the under face 21 of the clamping member will be clamped firmly against the top face of the tympan sheet.

The presence of the shoulders 23 and 24 which are thus formed in the tympan sheet, serve to hold the gage firmly in its clamped position and the shoulder 23 serves to prevent the gage from being displaced backwardly by any pressure which may be applied to the gage head 15 when heavy material such as cardboard is fed into position for printing.

My improved gage is provided with means which limit the depth to which the biting edges can be sunk into the top and bottom surfaces of the tympan sheet when the gage is clamped

thereto. For this purpose the base portion 5 is provided with a forwardly extending tongue 25 situated centrally of the biting edge 17 thereby dividing said edge into two sections, and the edge face 19 of the gage head 15 is provided with a shallow notch 26 which registers with the tongue 25, said notch having a depth less than half the thickness of the tympan sheet. Said notch 26 thus divides the edge face 19 of the gage head into two sections and also similarly divides the biting edge 18 of the gage head into two sections.

When the gage is clamped to a tympan sheet 2, the biting edge 18 of each section of the tympan sheet engaging face 19 of the gage head will be sunk into the top face of the tympan sheet while the portion of the tympan sheet which rests on the tongue 25 will be clamped between said tongue and the bottom of the notch 26. The engagement of the bottom of the notch 26 with the portion of the tympan sheet resting on the tongue 25 limits the downward displacing movement of the tympan sheet engaging surface 19, and since said notch has a depth less than half the thickness of the tympan sheet, the shoulders 23 and 24 will also each have a depth less than half the thickness of the tympan sheet. The above operations result in the formation of two indentations in the top face of the tympan sheet and two shoulders 23, one formed by each section of the end edge face 19. The end walls 28 of the notch 26 also cooperate with the tongue 25 to form shoulders 31 in the top surface of the tympan sheet, at the inner ends of shoulders 23 made by said biting edge sections 18.

The base 5 is also provided at each side with a wing portion 29, said wings supporting the tympan sheet at each side of the gage head during the clamping operation and cooperating with the end faces 21 of the gage head to form shoulders 30 in the tympan sheet at the outside ends of the shoulders 23 made by said biting edge sections 18.

When the gage is clamped to the tympan sheet, it is securely held in position to a certain extent by the clamping of the tympan sheet between the bottom face 21 of the clamping member and the base, but to a much greater extent by the shoulders 23, 24, 30 and 31 formed as above described.

The forwardly facing shoulders 23 constitute abutments which cooperate with the gage head 15 to prevent the gage from being displaced backwardly, and the rearwardly facing shoulders 24 cooperate with the end face 16 of the base to prevent the gage from being displaced in a forwardly direction. The shoulders 30 and 31 cooperate with the gage head to prevent any sideways movement of the gage.

In fact, a gage embodying my invention will, when clamped to the tympan sheet, have such a firm grip thereon that if a pulling force is applied to the gage, the tympan sheet will be torn before any slippage of the gage on the tympan sheet occurs.

My improved gage also has the advantage that it will be securely held in position even if it is clamped to the tympan sheet with the gage head within $\frac{1}{8}$ " of the edge thereof. As stated above, the principal clamping effect of the gage on the tympan sheet is produced by the manner in which the biting edges 18 and 17 bite into the top and bottom surfaces of the tympan sheet thereby to form the shoulders 23 and 24, and this clamping effect will be produced even though the edge of the tympan sheet extends only about $\frac{1}{8}$ " or so inside of the vertical plane of the biting edges.

Another advantage of my improved gage relates to the ease with which the gage can be clamped to a tympan sheet. The wings 29 act as guides to assist in entering the edge of the tympan sheet between the gage head 15 and the base, and after the tympan sheet has been thus entered between these parts, the printer can readily adjust the gage into its correct position with one hand, and while holding the gage in this position, he can press the clamp-actuating member 8 into its operative position with one of his fingers and without loosening his hold on the gage. This is a decided advantage over those gages which require the use of both hands to clamp them in position.

Another advantageous feature of the gage is that it has a relatively small vertical dimension so that the gage, when in use, will not interfere with type which are set to print close to the edge of the sheet 3.

The gage herein shown is provided with a guard member 32 which extends through openings 33 formed in the walls 14 and 15 of the gage head and which serves to prevent the edge of the sheet 3, when fed into position against the gage, from curling up sufficiently to slide up over the top of the gage head.

This guard member 32 may be a thin strip of metal and the rear end 34 thereof is shown as extending through a notch 35 formed in the presser foot portion 9. This guard member can be easily removed if its presence is not necessary, as for instance, when the sheets to be printed are in the form of cards or cardboard or other heavy material. It can be easily inserted into position, however, when its use is desirable to prevent the edge of the sheet 3 from curling up.

My improved gage has a further advantage that its hold on the tympan sheet will be just as effective on a thin sheet as on a thick sheet because regardless of the thickness of the tympan sheet, the operation of clamping the gage to the sheet produces the forwardly facing shoulder 23 and the rearwardly facing shoulder 24 which are important factors in securely anchoring the gage to the tympan sheet.

I claim:

1. A printer's gage comprising a base plate having a tympan sheet supporting surface terminating at its front end in a biting edge, a clamping member presenting a vertically extending work-positioning portion having at its lower end a tympan sheet engaging surface which is located immediately beyond the biting edge of the base plate, and also having a vertical inner wall which forms with the tympan sheet engaging surface a companion biting edge parallel to, above and in the same vertical plane as the biting edge of the base plate, means to apply a clamping pressure to the clamping member to press the tympan sheet engaging surface thereof against that unsupported portion of a tympan sheet resting on the base plate which lies immediately beyond the biting edge thereof, and

to displace said unsupported portion downwardly and to sink the biting edge of the clamping member into the top surface of the tympan sheet, thereby forming therein a forwardly facing shoulder, and also to sink the biting edge of the base plate into the bottom face of said tympan sheet, thereby to form therein a rearwardly facing shoulder which is in the same vertical plane as said forwardly facing shoulder, and means to limit the tympan sheet displacing movement of the tympan sheet engaging surface to less than half of the thickness of the tympan sheet.

2. A printer's gage comprising a base plate having a tympan sheet supporting surface terminating at its front end in a biting edge, a clamping member presenting a vertically extending work-positioning portion having at its lower end a tympan sheet engaging surface which is located immediately beyond the biting edge of the base plate, and also having a vertical inner wall which forms with the tympan sheet engaging surface a companion biting edge parallel to, above and in the same vertical plane as the biting edge of the base plate, means to apply a clamping pressure to the clamping member to press the tympan sheet engaging surface thereof against that unsupported portion of a tympan sheet resting on the base plate which lies immediately beyond the biting edge thereof, and to displace said unsupported portion downwardly and to sink the biting edge of the clamping member into the top surface of the tympan sheet, thereby forming therein a forwardly facing shoulder, and also to sink the biting edge of the base plate into the bottom face of said tympan sheet, thereby to form therein a rearwardly facing shoulder which is in the same vertical plane as said forwardly facing shoulder, said base plate having a tongue projecting forwardly from its biting edge centrally thereof, which tongue divides the biting edge into two sections, and said tympan sheet engaging surface of the clamping member having a shallow notch registering with the tongue and which cooperates therewith to limit the downward displacing movement of said tympan sheet engaging surface.
